United States Patent Office

Des. 224,284

Patented July 18, 1972

224,284

BED SPRING UNIT OR SIMILAR ARTICLE

Richard C. Roe, Palatine, Ill., and Wilton J. Davis,
Rensselaer, Ind., assignors to Sealy, Inc., Chicago, Ill.

Filed Apr. 2, 1970, Ser. No. 22,430

Term of patent 14 years

Int. Cl. D6—01

U.S. Cl. D5—2

Fig. 1.

FIG.2.

FIG.3.

fig.4.

FIG. 5.

FIG. 1 is a top plan view of a bed spring unit or similar article, showing one form of my new design as for a twin bed wherein 22 rows of coils are arranged in a 2-7-2 row transverse sequence;

FIG. 2 is a fragmentary enlarged scale perspective view;

FIG. 3 is a fragmentary enlarged scale top plan view;

FIG. 4 is a top plan view of a bed spring unit showing a second form of my new design as for a double bed wherein 22 rows of coils are arranged in a 2-11-2 row transverse sequence; and

FIG. 5 is a top plan view of a bed spring unit showing a third form of my new design as for a queen sized bed wherein 24 rows of coils are arranged in a 2-13-2 transverse sequence.

We claim:

The ornamental design for a bed spring unit or similar article, as shown and described,
